FIG. 1

FIG. 3

FIG. 2

FIG. 4

FIG. 5

FIG. 6

FIG. 7

FIG. 1 is a front perspective view taken from the left side of a riding rotary mower embodying my new design;

FIG. 2 is a front perspective view taken from the right side thereof;

FIG. 3 is a front view thereof taken slightly in perspective;

FIG. 4 is a rear view thereof taken slightly in perspective;

FIG. 5 is a top view thereof taken slightly in perspective;

FIG. 6 is a left side view thereof taken slightly in perspective;

FIG. 7 is a right side view thereof taken slightly in perspective;

FIG. 8 is a front perspective view taken from the left side of a modified form of the design shown in FIG. 1;

FIG. 9 is a left side elevational view of FIG. 8;

FIG. 10 is a top view of FIG. 8 taken slightly in perspective; and

FIG. 11 is a rear perspective view taken from the right side of FIG. 8.

The dominant features of my design reside in the full line portions of the drawings.

This application is a continuation of my design applications, Serial Nos. D-62,410 and D-62,411, both filed October 7, 1960 and now abandoned.

I claim:

The ornamental design for a riding rotary mower, substantially as shown and described.
